(57) CLAIM

The ornamental design for a swimsuit top, as shown and described.

DESCRIPTION

FIG. 1 is a perspective view of a swimsuit top showing the new design according to one embodiment of the present invention;

FIG. 2 is a front view of the swimsuit top of FIG. 1;

FIG. 3 is a rear view of the swimsuit top of FIG. 1;

FIG. 4 is a first side view of the swimsuit top of FIG. 1;

FIG. 5 is a second, opposing side view of the swimsuit top of FIG. 1;

FIG. 6 is a top view of the swimsuit top of FIG. 1; and,

FIG. 7 is a bottom view swimsuit top of FIG. 1.

The surface stipplings of FIGS. 1-7 are provided to show the surface contours of the swimsuit top.

The broken lines shown on the swimsuit top are unclaimed features of the article.
